[57] CLAIM

The ornamental design for a combined clamp and table stand, as shown and described.

DESCRIPTION

FIG. 1 is a front and top-left perspective view of a combined clamp and table stand showing my new design;

FIG. 2 is a rear and bottom-right perspective view thereof;

FIG. 3 is a front and top left perspective view thereof with the tripod legs extended;

FIG. 4 is a bottom plan view of FIG. 3.
